Des. 232,846
Patented Sept. 17, 1974

232,846

SALT BLOCK HOLDER

Leonard J. Fusco, Scott Road, Prospect, Conn. 06712,
and Robert J. Perazzini, 456 Prospect Road, Water-
bury, Conn. 06706

Filed July 21, 1972, Ser. No. 274,091

Term of patent 14 years

Int. Cl. D30—03
U.S. Cl. D30—13

FIG. 1

FIG. 2

FIG. 3

FIG. 4

FIG. 5

FIG. 6

FIG. 1 is a front and top perspective view of a salt block holder, showing my new design.

FIG. 2 is a top plan view;

FIG. 3 is a bottom plan view;

FIG. 4 is a front elevational view;

FIG. 5 is a rear elevational view; and

FIG. 6 is a side elevational view thereof, the opposite side being substantially a mirror image thereof.

We claim:

The ornamental design for a salt block holder, as shown and described.
